G. R. BROWN

ELECTRIC FUSE

Filed June 13, 1924

Inventor:
George R. Brown,
by *Wm. D. Scott*
His Attorney.

UNITED STATES PATENT OFFICE.

GEORGE R. BROWN, OF BRIDGEPORT, CONNECTICUT, ASSIGNOR TO GENERAL ELECTRIC COMPANY, A CORPORATION OF NEW YORK.

ELECTRIC FUSE.

Application filed June 13, 1924. Serial No. 719,776.

The present invention relates to electric safety devices and more especially to electric fuses designed to be intercalated in an electric circuit, and adapted, in case of an excess current flowing in the circuit, to melt or blow and interrupt the circuit.

Where an electric fuse is blown under the action of a suddenly applied overload or a short circuit, the transformation of the metal of the fuse into fused or gaseous state is often accompanied by a heavy explosion which disrupts any enclosure or encasement about the fuse intended to protect persons and things from flying particles of molten metal. The larger the fuse the more serious are the consequences of its blowing under short circuit action.

The object of my invention is the provision of an improved electric fuse which shall be adapted, even when of high current-carrying capacity, to function quietly and without objectionable detonation or explosive action.

It is well known that two or more similar conductors arranged in multiple in an electric circuit will respectively carry volumes of electric current in inverse proportion to their lengths or resistances, and that the time required to heat a conductor is proportional to the current flowing therein. I make use of these known facts in constructing an electric fuse so that its blowing of the several parts thereof will not be simultaneous but in succession to each other.

One embodiment of my invention is shown in perspective in the accompanying drawing.

It consists of a single strip 1 of sheet metal, such as zinc or lead tin alloy, having in its ends the customary slots 2 and 3 by which it is coupled to the binding posts of a fuse block or casing (not shown).

The fuse strip in its middle or body portion is divided into a plurality of conductor bars 4, 5, 6 and 7 of progressively differing lengths by punching therein narrow longitudinal holes 8, 9 and 10 of correspondingly different lengths.

By spacing the holes unequally, the widths of the multiple bars are made of unequal widths and as will appear later the longest bar 7 is preferably made narrow or more attenuated than the others.

When such a fuse construction is subjected to the passage of electric current, the latter will not divide equally between the four bars but in inverse proportion to their respective resistances so that when an abnormal flow takes place the shortest bar 4 disrupts or blows first, then bars 5, 6 and 7 in seriatim. Moreover, the final break of the circuit takes place in the longest bar 7 and the arc that tends to form confines itself to the volatilization of that bar until the gap produced is too great for the arc to persist, thus breaking the circuit on an attenuated conductor with the incident volatilization of only a small percentage of metal that occurs upon the blowing of the single bar fuses in common use on similar service.

By variation in the relative lengths of the bars, or by variation of their relative widths, or by both together, the performance of my fuse may be varied to meet the conditions of any service desired.

While I have shown and described the best embodiment of the invention known to me, I do not desire to be restricted thereto.

What I claim as new and desire to secure by Letters Patent of the United States, is,—

1. A unitary fuse link comprising a sheet of metal having longitudinal apertures of differing lengths in the body thereof to provide multiple bars of differing conductive capacities.

2. A fuse link comprising multiple conductor elements having different conductive capacities, and end members integrally connecting the opposite ends of the elements and adapted to be secured to circuit terminals.

In witness whereof, I have hereunto set my hand this eleventh day of June, 1924.

GEORGE R. BROWN.
